UNITED STATES PATENT OFFICE

134,375

DESIGN FOR AN EMBROIDERED LACE

Otto Raphael, Teaneck, N. J., assignor to Solomon & Birnbaum, Inc., New York, N. Y.

Application April 17, 1942, Serial No. 106,599

Term of patent 3½ years

To all whom it may concern:

Be it known that I, Otto Raphael, a citizen of the United States, residing in Teaneck, county of Bergen, State of New Jersey, have invented a new, original, and ornamental Design for an Embroidered Lace, of which the following is a specification, reference being had to the accompanying drawing, forming a part thereof.

The figure is a plan view of an embroidered lace showing my new design. The dot and dash lines on the drawing outline substantially the design unit, which unit is repeated in regular succession as indicated by the extensions beyond the unit boundaries.

I claim:

The ornamental design for an embroidered lace, as shown and described.

OTTO RAPHAEL.
